RAYMOND BANTON, OF GREELEY, COLORADO.

MEANS FOR GUARDING AGAINST THE UNAUTHORIZED RECEIVING OF RADIO-COMMUNICATIONS.

Application filed July 18, 1922. Serial No. 575,872.

This invention relates to the synchronous control of the receiving and the sending sets of space or wireless intelligence transmission systems broadly, and particularly embodies novel means for guarding against the unauthorized receiving of radio communications.

The invention has been more especially devised with reference to radio telephony, or radiophone receiving and transmitting sets, and for simplicity of illustration and description it will accordingly be disclosed in such particular relations. It is to be understood at the outset, however, that in so specifically disclosing the same there is no intention of imposing thereon any real unnecessary limitations, because some of the features of the improvements no doubt, at least from certain aspects, might be satisfactorily employed in other analogous relations.

It is understood that radiophone communications and recitals of numerous and varying characters are being broadcasted under government licenses and restrictions both with reference to the wave lengths employed as well as to the starting time and duration of such authorized use, and heretofore it has been possible for anyone, having a properly equipped radiophone receiving set of fairly comprehensive scope or range, to listen in on such communications generally, whether intended for public or comparatively private distribution, including highly instructive and artistic programs of entertainment which are received free of charge, by simply manipulating the regulator means of their receiving set, such as the detector and the tuning condenser or devices of analogous character, for bringing the instrument in receptive resonance or proper responsive attunement with reference to the wave length emissions from the transmitting or broadcasting station or stations. In other words it does not appear that, heretofore, there has been produced any substantially effective governing means, automatically or otherwise functioning in the nature of a "lock-out" as it were, for guarding against the unauthorized reception of such radiophone communications, which latter may be intended to be

of a more or less selectively secret character that should command monetary consideration.

The foregoing may not necessarily amount to a serious problem for the time being, even with particular reference to the broadcasting of artistic programs of entertainment, owing to the fact that at present there is a very active market for radiophone receiving sets by amateurs as well as others, and in order to keep that activity keenly alive the manufacturers or dealers in these instruments, or equipment therefor, will naturally provide such entertainments as long as they have to for the purpose of effecting large sales. On the other hand, concerning especially the commercialization of such programs of artistic entertainment embodying, amongst other features, instrumental and vocal renditions of varying characters, there can be no doubt but that the item of compensation will soon become a factor of vital importance, because substantial charges must eventually be made to bona fide subscribers, for the upkeep and reasonable profits of the business of promoting and furnishing such entertaining but costly service, requiring the expenditure of large sums for highly talented artists and expenses of operations generally.

It would seem to be obvious, therefore, that the enormous expenses of free broadcasting cannot go on indefinitely, because they will become prohibitive of the present practice of manufacturers, for instance, to broadcast these costly entertainments, as they now do more or less gratuitously, when and in the event that the sales of their goods pertaining to this art are materially cut down or lessened by the market demand therefor having been substantially supplied in point of wholesale distribution now liberally enjoyed. Assuredly, there will be no incentive for others than manufacturers or large dealers handling such equipment to send out such entertaining programs without substantial remunerative compensation for their special broadcasting service and expenses thereof, any more than that the average person could legitimately attend a

high class lecture, opera or other form of artistic entertainment without the payment of a prescribed admission fee.

- With these prefacing remarks, therefore, it may now be stated that the primary object of my invention has been to overcome the objections to the aforesaid arising situation by devising means for automatically providing a changeable or variant but ¹⁰ cordant or syntonus control as between the receiving set and transmitting set, whereby radio emanations from the latter of either continuously or periodically varying wave lengths may be synchronously picked up by ¹⁵ authorized subscribers only as an uninterrupted program, under automatic control at both ends, whereas non-subscribers will find it difficult, if not feasibly impossible, to keep their receiving sets in responsive attunement ²⁰ with the aforesaid varying wave length emissions from the transmitting station, and certainly not with any degree of actual continuity, as they will not have a translating key adapter as hereinafter referred to. ²⁵ In the accomplishment of my object, and as generically stated, I provide for a time-controlled sending key adapter at the transmitting set in couple with the usual wave changing device thereof, of whatever character or type or by whatever term styled, for either continuously or periodically varying the wave length emissions, which sending key adapter is produced in manifold quantities for each predetermined entertainment ³⁵ to be separately forwarded to each subscriber, in the nature of a paid ticket, and each of which is physically employed additionally as a translating key adapter that is installed at each subscribers' receiving set, in ⁴⁰ time controlled synchronous relation to the sending key adapter as well as in couple with the usual adjustable wave compensating for device of the receiving set, of whatever character or type or by whatever term styled ⁴⁵ although commonly referred to as the tuning condenser, for maintaining the receiving instrument in proper responsive attunement for the predetermined altering wave lengths broadcasted. ⁵⁰ The foregoing objects and stated functioning of my improvements, however, will be so clearly apparent as incidental to the following disclosure that no useful purpose would be served in further enlarging upon the same initially, and reference will be immediately had, therefore, to the accompanying drawings illustrating a practical embodiment of the improvements, in which drawings— ⁵⁵ Figure 1 is an elevational view of an embodiment of the physical parts of my improvements in combination, of which there may be broader or more specific conceptions as to details, and coupled in association with ⁶⁰ a wave responsive regulator device of a

radiophone receiving set, the view showing certain parts broken away and being more or less in the nature of a conventionally diagrammatic illustration.

Figure 2 is an elevational view analogous to that of Figure 1, but with the improvements illustrated as being associated with a wave changing device of a radiophone transmitting set;

Figure 3 is an elevational view taken at right angles to Figure 1 and as viewed from the left thereof;

Figure 4 is a plan view looking down on Figures 1 or 3, and inferentially looking down on Figure 2 as well;

Figure 5 is a chartographical plan view of a translating key adapter, being a duplicate of the sending key adapter, and illustrating an elongated type employed, for rectilinear actuation, where the wave length emissions are to be of a continuously varying character;

Figure 6 is a view analogous to Figure 5, but illustrating a modified form or type of the key adapter, as designed for rotary actuation; and

Figure 7 is a view analogous to Figure 5, but illustrating a modified form or type thereof, for employment where the wave length emissions are to be of a periodically varying character, as distinguished from a continuously varying or changeable wave length.

It may be suggested, however, that various equivalent forms or types of these key adapters might be employed, if desired, other than those specifically shown, which latter are primarily illustrated as a matter of preference only.

Also, it may not be amiss to state here the understanding that the length of the waves emanating at the sending station are theoretically determined by the length of the transmitting aerial wires, but practically by the inclusion in circuit therewith of an inductance element or regulating means for controlling the degree of impedance in the aerial circuit, and that parts of the receiving radiophone instrument must accordingly be adjustably regulated for the attunement of the instrument relatively to the frequency of the wave oscillations. Such regulating means, respectively, may perhaps be called by different names in practice, but wherever herein I employ the expression "wave responsive", whether it be the so-called tuning condenser or otherwise, I refer to that device or controlling means that attunes the receiving set through its antenna in actual syntony with the transmitting set and wherever I employ the expression "wave changing", I mean that device or frequency controlling means that regulates the length of the waves sent out from the transmitting station.

10 designates the shaft of an adjustable wave responsive device of the usual or any suitable type, which may be manually oscillated or turned back and forth by a disk or knob 11, its movements being indicated by a suitable scale arrangement shown as comprising a pointer 12 on the knob and graduations 13 on the wall support 14, journaling one end of the shaft 10 and illustrated in broken jagged outline.

15—16 designate means for oscillating the shaft 10, while 18 is a movably mounted bar for actuating the same. 15 may be a star wheel fixed to the shaft and 16 a rectilinearly operated perforated bar, although any other form of rack and pinion or equivalent means would suffice, and when the movable bar 18 is pivotally supported at its lower end, as shown at 19, then the bar 16 is likewise pivotally connected as at 17 to the upper end thereof. The inner edge face of the bar 18 provides a contact element, preferably an antifriction element as represented by the roller 20, which is associated in proper wiping relation with the key adapter as hereinafter more fully stated, and 21 conventionally illustrates means for holding the roller 20 up against the key adapter.

22 designates a shaft, which may be journaled as at 23, and is driven by any suitable time-controlled means, such as the minute hand shaft of a standardized clock mechanism, or as coupled up therewith or with the like. This shaft 22 in turn operates actuating means for the key adapter, which actuating means may consist of the star wheel 24 and perforated bar 25, or their equivalent, but the element 25 need not necessarily be a rigid bar, as it moves only in one direction, whereas the bar 16 should be rigid as it is a reciprocating bar.

The key adapter is indicated at 26—26^a—26^b in Figs. 2, 6 and 7, respectively, and at 26 in all of the other figures, with its keying edge face surface designated at 27 in Figs. 3, 4 and 5, at 27^a in Fig. 6, and at 27^b in Fig. 7.

When the adapter is in the nature of a flat elongated member, as illustrated at Figs. 5 and 7, it is detachably secured in any suitable way to the actuating element 25 for the operation of its keying surface in proper wiping association with the roller 20 of the pressure controlled movable bar 18; but when the key adapter is designed for rotary actuation, as at Fig. 6, it is obvious that it would be detachably mounted by the shaft 22 or its equivalent. Also, it is to be understood that the translating key adapters are always duplicates of the sending key adapter employed at the time, at least in so far as the contours of their keying surfaces are concerned.

With reference to Fig. 5, it will be ob-

served that the keying surface 27 is of substantially continuing variant contour, as is likewise the keying surface 27^a of Fig. 6, while the keying surface 27^b of Fig. 7 is a periodically variant surface comprising 70 planetary steps of varying depths and lengths, the longitudinal parallel lines 28 being intended as a chartographical illustration designating wave lengths in meters, and the transverse parallel lines 30 as divisions 75 of time during which such wave lengths are licensed to be employed. These lines are also shown as continuing outside of the actual zone of the key adapter as at 29 and 31, respectively, and all of the analogous parts or 80 designations in Figs. 6 and 7 are indicated by the same numerals with the addition of the exponents "a" and "b". Although a chartographical designation of wave lengths of 85 from 360 to 375 meters with a time designation of from 6 p. m. to 8.45 p. m. are illustrated by the drawings, it is of course to be understood that this is merely illustrative and not intended as limitations at all, for the invention is equally applicable for use with 90 any other proper wave lengths or at any other times, under licensed control and government regulations. It is also to be understood that the bodies of the key adapters may 95 actually embody these chartographical designations, which may be of advantage to the subscriber in properly adjusting his receiving instrument, without delay at any time, in the event that he is late for the beginning 100 of the program, or for any one of say a weekly series of programs, that his purchased ticket-translating-key-adapter calls for, but this is not essentially necessary to the actual invention involved.

At Figure 2, which conventionally indicates the transmitting or broadcasting station, the same or analogous parts as of Figure 1 are indicated by the same reference numerals but with the prime sign (') exponent added, although it is to be understood that the shaft 10', instead of operating a "wave responsive" device, in reality actuates a "wave changing" device, either directly or through intermediate connections. In some instances, however, the shaft 10' and star wheel 15' would doubtless be omitted, or at 110 least that could be done, and the bar 16' coupled directly or indirectly in any suitable manner with the proper movable element 115 of the wave changing device. By analogy, this would also be true with reference to 120 Figure 1.

At this point it may be finally emphasized that the actuating means for the sending key adapter 26', illustrated as embodying the shaft 22', star wheel 24' and an element analogous to the element 25 but not appearing in the view, are so time-controlled 125 in their operations that the analogous parts 130 of the receiving set may be maintained in

true synchronism therewith, and this may be done in any preferred way, such as by the employment of standardized clock mechanism, or synchronizing motors, means or systems of any suitable character, the essentials being that the translating key adapters should be actuated in congruently registering synchronism with the sending key adapter, and with reference to their wiping control or keying surfaces as before fully referred to.

Operation.

Assuming that the broadcasting station is employing a sending key adapter as at Fig. 5, of which the subscribing stations have been supplied with their paid for ticket translating duplicates. The program starts at 6 p. m. on a wave length of 360 meters, which wave length gradually increases until at between 6.15 and 6.45 o'clock the waves are being sent out at lengths of 363 meters, thereafter continuously increasing again until at around 7.00 o'clock they have reached lengths of 368 meters, from whence they decrease to 365 meters around 7.30 o'clock, then are again on the ascendant until around 8 o'clock, when they have reached their maximum lengths on the scale of 370 meters, after which they recede again and so on as illustrated. As the sending key moves along at the transmitting station, under time controlled actuation, it will be obvious that as the keying surface thereof wipes over the roller 20', the movable bar 18' will be moved back and forth, and through the connection 16' will in like manner operate the proper movable element of the wave changing device, for continuously varying the wave length emissions in the degrees as just previously recited. The receiving station or stations having properly adjusted their translating key adapters, at the beginning of the program or at any time within the limits of its duration, as will be fully understood from all of the foregoing, it follows that a synchronous actuation will likewise be carried on at each subscribing station entitled to listen in on that program, for as the keying surface 27 of the translating key wipes over the roller 20, the movable bar 18 is caused to be actuated back and forth, congruently with the actuation of the bar 18', and by means of its connection 16, or its equivalent, will in like manner operate the proper movable part of the wave responsive device for automatically keeping the receiving instrument in sympathy with the sending instrument regardless of the wave frequency or fluctuations at the broadcasting station. After initial adjustment, therefore, the receiving station is required to do no further adjusting, as this is all provided for automatically, but a receiving station not having any such key adapter would find it dif-

ficult, if not feasibly impossible, to keep their instruments constantly manipulated manually for following the program uninterrupted.

From the foregoing description, it will be obvious that the same operations in principle will follow when employing a rotatable key adapter at either or both ends, excepting that the mounting of the key adapter and its actual actuation would be slightly different, although clearly apparent without further description.

Of course, any one particular broadcasting station may not be able to obtain a government license for the use of certain different wave lengths during a specified period of time, but contractual arrangements could be made as between licensees for exchanging or borrowing the use of their wave lengths during a limited period of their time, so that there would be no especial air interference which is aimed to be strictly guarded against by restrictive regulations.

Finally, a key adapter might be employed which would have a keying surface that would only periodically vary the wave length emissions, instead of continuously doing so, and which in many cases might be more desirable anyhow than the employment of ones whereby a program is rendered during a predetermined space of time and with a continuously variant wave length as before set forth. Such a modified key adapter is clearly outlined at Figure 7 but its operation, when viewed in connection with all of the foregoing, will be self-apparent it is believed, without a more lengthy and repetitious description thereof.

Having thus fully disclosed my invention, it will nevertheless be understood, as has heretofore been intimated, that I do not necessarily confine myself to all of the details exactly as disclosed, excepting as they may come within the terms of the ensuing claim, or equivalent steps or combinations of elements, or as fairly interpreted in the light of the specification if necessary, for it will be obvious that various alterations as to details might be made without departing from the gist or the spirit of the invention.

What I do claim, as new and patentable, is:—

In systems of the character disclosed, embodying a transmitting set, having adjustable wave changing means, and a receiving set having adjustable wave responsive means, the combination of a swinging support associated with said receiving set, connecting means between said swinging support and said wave responsive means for automatically adjusting the latter in reverse directions by the swinging movements of the former, a translating key adapter, providing a keying surface of predetermined multiform irregularly successive varying outline, mova-

bly mounted in association with said swinging support, means for maintaining said swinging support in operative association with said keying surface, and actuating means for said adapter for causing said keying surface to wipe over said swinging support, the said actuating means being under synchronic control relatively to an equivalent combination of elements at the transmitting set that automatically adjusts the wave changing means of the latter. ¹⁰
In testimony whereof, I affix my signature.

RAYMOND BAINTON.
